UNITED STATES PATENT OFFICE.

GEORGE P. JACKSON, OF FLUSHING, NEW YORK, ASSIGNOR TO INTERNATIONAL COMBUSTION ENGINEERING CORPORATION, A CORPORATION OF DELAWARE.

BOILER FURNACE.

Application filed September 10, 1925. Serial No. 55,483.

This invention relates to boiler furnaces and has to do particularly with furnaces, the combustion space of which is largely defined by evaporating elements of a boiler.

5 The invention is especially useful in pulverized coal burning stationary boiler installations and will be described as thus applied.

One of the primary objects of the invention 10 is to simplify the connections in such an installation, to provide for effective circulation and the prevention of siphoning and to provide for expansion and contraction.

How the foregoing objects, together with 15 such others as many hereinafter appear, or are incident to my invention, are realized, is illustrated in preferred form in the accompanying drawings, wherein

Fig. 1 is a vertical section thru a boiler and 20 a boiler furnace embodying my improvements, and

Fig. 2 is an enlarged fragmentary view, partly in section, illustrating details of the invention and

25 Fig. 3 is a fragmentary cross sectional view illustrating such details.

Referring now to Fig. 1, the reference character A denotes a combustion chamber having the outlet 7 in its upper part over which extend boiler tubes 8 as indicated in dotted lines.

A large portion of each side wall of the combustion chamber is provided with a water wall B composed of tubes 9, preferably provided with longitudinally extending fins 10 as 35 illustrated in Fig. 3. The rear wall of the furnace is largely composed of a water wall C formed of tubes 11 having fins 10 as above described. The upper ends of the tubes 9 of the side water walls B are bent outwardly to 40 extend thru the side walls for connection into the headers 12 and the lower ends of such tubes pass outwardly thru the side walls for connection into the headers 13. The upper ends of the tubes 11 extend thru the rear wall 45 for connection into the header 14, and the lower ends of such tubes pass to the exterior for connection into the junction boxes 15 to be described.

A screen D is located in the lower part of 50 the combustion space, such screen being composed of tubes 16 relatively widely spaced apart to permit the gravitating refuse to pass freely therethru to the hopper 17 therebelow. The front ends of these tubes are connected

into the header 18 and the rear ends of these 55 tubes connect into the junction boxes 15.

Downcomer pipes 19 lead from the drum 20 of the boiler (which is of the cross drum type, altho any other suitable form of boiler may be employed), such pipes dividing into 60 two branches 21 and 22, the branch 21 leading to the header 18 and the branch 22 leading to the headers 13. These branches are of sinuous form to take care of expansion and contraction. From each header 12 an upcomer 65 pipe 23 leads to a box 24 from which a plurality of small pipes 25 lead to the drum 20 to complete the circuit.

From one end of the header 14 an upcomer pipe 26 leads to a box 27 which connects with 70 certain of the pipes 25, and from the other end of the header 14 a similar upcomer pipe 28 leads to a similar box similarly connected.

Since the screen D has about one half the 75 number of tubes of which the rear water wall C is formed, the junction boxes 15 are approximately Y shaped having three openings, one below and two above to respectively receive one of the pipes 16 and two of the 80 pipes 11.

Pulverized coal is admitted into the upper part of the combustion chamber in a downward direction thru a row of burners E, the fuel and flame descending downwardly until their momentum is overcome by the draft, 85 whereupon the fuel and flame stream reverses in U shape with combustion practically completed before the tubes 8 are reached. The tubes 9, 11 and 16 being subjected to radiant heat perform by far the largest proportion 90 of the evaporation done by the boiler and the circulation therethru is very rapid indeed, to which end I have found it useful to cause the upcomer pipes to discharge into the plurality of small branches leading to different parts 95 of the drum to avoid siphoning and yet to permit a free flow of steam.

The various bends in the tubes take care of expansion and contraction and the junction boxes form an effective means for coupling 100 the tubes of the bottom screen D to the tubes of the rear water wall.

What I claim is:

In combination in a pulverized fuel burning furnace, a water screen in the lower part 105 thereof composed of relatively widely spaced tubes which project through a wall of the furnace, a water wall composed of relatively

closely spaced exposed tubes along an upright wall of the furnace, the ends of said latter tubes being bent and extending at an angle through a wall of the furnace and terminating 5 adjacent the ends of the water screen tubes, there being substantially twice as many tubes in the water wall as in the water screen, a junction box, V-shaped in side elevation and inverted triangular shaped in front elevation, 10 said junction box having two tube holes in the upper part thereof in angles of the triangle

into which pairs of the said water wall tubes are connected and a single tube hole in the lower angle of said triangle into which a single tube of the said water screen is connected, said tube holes facing in the same general direction, and means connecting the screen and water wall into the circulation of the boiler.

In testimony whereof, I have hereunto 20 signed my name:

GEORGE P. JACKSON.
